US0D1091966S

(12) **United States Design Patent** (10) Patent No.: **US D1,091,966 S**
(45) Date of Patent: ** Sep. 2, 2025

(54) **PET RESTRAINT**

(71) Applicant: **Clement Robert Hipple**, Philadelphia, PA (US)

(72) Inventor: **Clement Robert Hipple**, Philadelphia, PA (US)

(**) Term: **15 Years**

(21) Appl. No.: **29/915,492**

(22) Filed: **Nov. 6, 2023**

(51) LOC (15) Cl. **30-04**
(52) U.S. Cl.

USPC **D30/151**; D30/144; D30/158

(58) **Field of Classification Search**

USPC D30/144, 145, 151, 152, 156, 158, 199;
D24/190; D2/718, 719, 860, 861, 864
CPC A01K 15/04; A01K 13/006; A01K 13/00;
A01K 13/008

Primary Examiner — Kendra Leslie Hamilton

(57) **CLAIM**

The ornamental design for a pet restraint, as shown and described.

DESCRIPTION

FIG. 1 is a top front perspective view of a pet restraint showing my new design;

FIG. 2 is a bottom rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right elevational view thereof;

FIG. 9 is a top front perspective view thereof, wherein the pet restraint is shown in a fastened configuration, and wherein the pet restraint is shown with front and rear support straps;

FIG. 10 is a top rear perspective view thereof;

FIG. 11 is a top front perspective view thereof, wherein the pet restraint is shown restraining a cat, and wherein the support straps are shown restraining the cat; and,
FIG. 12 is a top plan view thereof.

The broken lines showing buckles in FIG. 1-12, the broken lines showing hook and loop fasteners in FIG. 2-4, 6, and 8-12, the broken lines showing support straps in FIG. 9-12, and the broken lines showing a cat in FIG. 11-12 are included for the purpose of illustrating environmental structure and form no part of the claimed design.

1 Claim, 12 Drawing Sheets
